Fig. 4.

Fig. 2.

This technical drawing illustrates a gear assembly. The main gear, labeled 18, is shown with its teeth in a fan-like arrangement. A smaller gear, labeled 16, is meshed with the main gear. A vertical shaft, labeled 1, passes through the center of the gears. A housing or housing part, labeled 21, is shown on the left side. Various other components are labeled with numbers: 22, 23, 19, 18, 19', 18', 17, 18a, 20, 18b, 16, 21, 17, 16, and 15. A large letter 'F' is located in the bottom right corner of the drawing area.

Radio Corporation of America, a corporation
of Delaware

Application August 21, 1945, Serial No. 611,720

9 Claims. (Cl. 250—175)

1

This invention relates to television tubes and multiplier dynodes therefor.

In my co-pending application, filed September 16, 1944, Serial No. 554,494, now U. S. Patent No. 2,433,941, issued January 6, 1948, I have disclosed a type of multiplier dynode having a plurality of radiating inclined blades adapted to be positioned over the gun behind the first anode, which act as the second and subsequent dynodes of the multipliers. This construction has proved quite efficient due, among other things, to the symmetrical location around and back of the beam path. To shield the second and subsequent dynodes from the potentials of the electrode members in front, a shield screen was conductively fastened to these dynode units, so that electrons would be more effectively attracted to the next dynode in the rear. The bombarding electrons passed through the meshes of this screen effectively, but the screen, of course, "casts a shadow" on the multiplier blades and collects electrons in proportion thereto. This, with other characteristics of that form of multiplier, limited the efficiency to about 85% of the secondary emission ratio of the dynode.

It is an object of this invention to construct a multiplier dynode that obviates the use of a shielding screen in a multiplier unit for protecting the emitted secondary electrons from the suppressing field of preceding electrodes.

Another object of the invention is to construct a multiplier dynode assembly around the gun, so that the dynode blades themselves shield the emitted secondary electrons from preceding fields without reduction of the entrance area for the bombarding primary electrons.

Other objects will appear in the following specification, reference being had to the drawing, in which:

Fig. 1 is a section through the dynode units of the multiplier, being taken through the plane 1—1 in Figs. 2 and 3, viewed in the direction of the arrows.

Fig. 2 is a front view of a dynode unit of Fig. 1, this figure being broken away to show only one-quarter of the complete circular dynode.

Fig. 3 is a diagrammatic partial sectional illustration of the manner of stamping and the arrangement of the dynode blades, the section being taken on the line 3—3 of Fig. 1, certain parts being omitted for clarity of illustration.

Fig. 4 is a sectional view similar to that of Fig. 3 illustrating a different way of stamping the vanes.

Referring to the drawing, the cathode beam

2

tube in which the multiplier dynodes are illustrated consists of a cathode 1 heated by coil 2. The front end of this cathode will have a suitable surface or coating for emitting electrons when heated. Grid or control member 3 surrounds the cathode and has a small opening 4 in its end adjacent the center of the cathode. This opening is shown greatly enlarged over the 40 mil diameter ordinarily employed. First anode 5 surrounds the grid and has an end 6 adjacent, and in front of, the grid 3. This end is of suitable metal, or is coated with material for good emission of secondary electrons under bombardment by the returning portion 7 of the beam 8, which is projected at high velocity through the opening 9 in front of the opening 4 in the grid. The opening 9 is usually of the order of 2 mils in diameter. Surrounding the tubular first anode 5 may be an insulating tube 10 on which are mounted the dynodes. The dynodes also may be supported from the periphery, as later explained, but either type of support may be used alone, if desired.

As many multiplying dynodes as desired may be assembled on the first anode back of the first dynode 6, but by way of example I have shown four. To provide for proper entry of the secondary electrons in my improved dynodes, it is preferable to use a second dynode 11 with shield screen 12 welded or soldered thereto, as in my 25 30 35 40 45 50 55 said application. After this type of second dynode I use my improved type, consisting of three dynodes, 13, 14, 15 having radial vanes formed into trough-shaped members. These constitute the third, fourth and fifth multiplying stages, the first stage being the disc 6, as already indicated. There would be a final collecting electrode in a complete installation mounted on the gun to the rear of the dynode 15, but this is not a part of the invention claimed herein and it is shown only in dotted lines in the diagrammatic illustration of Fig. 3. The dynodes 13, 14, 15 have the same general construction, but the troughs of alternate dynodes extend in reverse directions, as made clear in Fig. 3.

Each dynode disc of this invention is stamped from a sheet of about 5 mils thickness of silver-magnesium alloy or other suitable metal having good secondary emission properties. The dynode is circular and has a central circular hole 16 of the proper diameter to fit over the insulating tube 10 or is properly spaced from the tubular first anode 5, if the insulation is to be omitted. The dynodes may be stamped in different ways, two of which are shown in the drawing in Figs. 3 and 4. The form illustrated in Figs. 1 and 2

is shown in Fig. 3. In this form the vanes are cut by suitable dies and tools from the disc 17 at the radial lines passing through points 18 and 18' and bent 45° counter-clockwise around the radial lines passing through points 19 and 19', leaving openings through the disc between the radial lines 18, 19'. The portion between the radial lines 18 and 19 and 18', 19' is uncut metal and may be made as small as desired. The vanes are of such length as to leave the disc uncut at the periphery at 18a and around the opening 16 at 18b, to give the disc proper rigidity. Then, the outer half 19a of the stamped-out blades is bent an additional 90° to form troughs 20. Thus, one side is bent 45° to the plane of the disc and the other one 135°. While the particular angle between the sides of the trough need not be 90°, as given, this is a suitable angle for efficient operation of the dynodes.

The periphery 18a of the disc is then clamped over a supporting ring 21 of 30 mil nichrome wire or equivalent and to the surface of this clamped-over portion may be welded, or otherwise secured, supporting brackets 22 properly spaced around the periphery. As indicated in the drawing, there are four of such brackets. These would be fastened to suitable supporting insulation rods 23 within the tube, for example, as in the application of S. V. Forgue, filed February 7, 1946, Serial No. 646,075, but since the supporting means is not part of the invention claimed herein, it is not shown in complete detail.

The troughs of the third dynode 13 are shown facing to the right in Fig. 3, though of course this could be the reverse without changing the invention. The fourth dynode 14 is stamped so that the troughs face in a direction reverse to that of the previous dynode 13 and is positioned with one side 19a substantially parallel to and properly spaced from a side of a trough of dynode 13. The troughs of the fifth dynode 15 are stamped similarly to those of the third dynode 13, so as to face in an opposite direction to those of the fourth dynode, with a side 19a substantially parallel to and spaced from a side of a trough of dynode 14. All of this arrangement is clearly shown in Fig. 3.

If there are to be additional multiplier dynodes, they would be stamped, arranged and assembled in a way that will now be apparent without further description.

The manner in which my improved multiplier dynodes operate will now be explained:

The various electrodes would be connected to suitable terminals V₁ to V₇, having voltages known to those skilled in the art, and these need not be specified. The electrons emitted by the end of the cathode 1 are controlled by the grid 3 and projected at high velocity as a beam 8 through the small opening 9 in the end of the first anode 5. The beam would be controlled in the usual way by deflecting fields, wall coating and decelerating ring, or equivalents, as disclosed, for example, in my said application. After being decelerated to the target of approximately cathode potential, the electrons not landing on the target would return and be accelerated as at 7 to the surface of disc 6 constituting the first dynode. The returning electrons of the beam would thus bombard the first dynode over the disc surface and secondary electrons would be emitted and attracted around the periphery, as at 24, to the rear of the first dynode 6 through shield screen 25. The electrons 24 hit the vanes 26 of the second dynode and produce secondary

electrons, as at 27 (Fig. 3), as in my said application. These vanes are stamped 45° from the disc 17 and are preferably twice the width of the blades or sides of the trough shaped stampings of dynodes 13, 14 and 15. The secondary electrons 27, instead of passing through a screen attached to the succeeding dynode, as in that prior application, pass directly to the surfaces 28 of the troughs of the first dynode 13. Since there is no shield screen for the electrons to pass through, there is no shadow cast on the surfaces of sides 28 and all electrons land thereon under influence of the higher potential of third dynode 13. These secondary electrons 27 are suitably shielded from the preceding potentials by sides 19a of the troughs of the third dynode, without using a screen. Electrons in an electrostatic field are accelerated in paths perpendicular to the equipotential lines thereof and the field is such that the electrons leaving vanes 26 cannot take the shorter paths to the sides or vanes of the troughs 20 that are parallel thereto but must continue on to the sides 28 perpendicular to vanes 26. A complete explanation of the theory of the travel of electrons in multiplier fields is contained in an article by V. K. Zworykin and J. A. Rajchman, in I. R. E. of September 1939, page 558, and further explanation need not be given here. The secondary electrons emitted by the sides 28 are accelerated to the sides 31 of the next dynode 14 without passing through any screen electrodes. The sides 19a of the troughs of the fourth dynode adequately shield these secondaries from preceding potentials. Hence, no shadow is cast on the emitting surfaces of sides 31 and all electrons land thereon. The secondary electrons emitted by the sides 31 of the troughs of the fourth dynode are attracted to the rear and bombard secondary electrons 33 from the sides 34 of the troughs of the fifth dynode, which are similarly shielded from previous potentials by the sides 19a. The secondaries 33 pass to a collector electrode 37, to which the output terminal of the multiplier would be connected.

In my invention I am able to get substantially 100% emission efficiency in the dynodes 13, 14 and 15, because no shield screens are used therewith. The sides of the troughs sufficiently modify the potential field distribution so that the secondary electrons emitted by the other sides of the troughs are attracted to succeeding dynodes without passing through shielding screens.

In Fig. 4 the method of stamping of the radial vanes is somewhat different. Instead of stamping the troughs out of single openings between 18 and 19' as in Fig. 3, one side 38 is stamped down in the figure and is bent clockwise 45° around the radial line passing through the point 39, being cut from the disc at the radial line intersecting the point 40. The other side of the trough is then stamped at the radial line of point 40 and bent 135° clockwise around the radial line at point 41 slightly spaced from point 39. In this method of stamping, the sides of each trough meet in the plane of the disc and the openings in the disc, through which the electrons pass, lie between the radial lines at points 39 and 41.

In the stamping method of both Figs. 3 and 4, the side of the trough stamped and bent the lesser angle of 45° has a web 42 connecting the outer and inner ends of the trough sides to the uncut rings 18a and 18b of the disc. The length of these end webs depends upon the malleability of the metal of the disc. In general, these webs will extend from the apex over a fraction, only, of the

ends, but the length is sufficient to add considerably to the rigidity of the dynode.

While I have chosen particular angles for the blades of the improved multiplier dynode, it will be understood that different angles may be chosen when desired.

Various modifications of the invention may be made without departing from the spirit of the invention.

Having described my invention, what I claim is:

1. A dynode disc for electron multipliers having a plurality of pairs of vanes stamped therefrom into troughs with the sides of the troughs making predetermined angles with each other and with the plane of the disc and the bisecting plane of the troughs being parallel to the disc to permit electrons to strike one side of the trough through the openings from which said vanes are stamped.

2. A dynode disc for electron multipliers having a plurality of pairs of vanes stamped therefrom into troughs with each side of the trough making an angle with the plane of the disc permitting electrons to strike a side of the trough through the openings from which said vanes are stamped, one of the sides of each trough being connected with the disc adjacent the periphery and central portion thereof and the bisecting plane of the troughs being parallel to and spaced from the disc.

3. A self-shielding dynode disc for electron multipliers having a plurality of pairs of vanes stamped therefrom into troughs with each side of the troughs making an angle to the plane of the disc and the bisecting plane of the troughs being parallel to and spaced from the disc, one side of each trough adapted to shield secondary electrons bombarded from the surface of the other side by electrons entering through the openings in the disc from which said vanes are stamped.

4. A self-shielding dynode disc for electron multipliers having a plurality of pairs of vanes stamped therefrom into right-angle troughs with one side of the trough making an angle of 45° to the plane of the disc and the bisecting plane of the troughs being parallel to and spaced from the disc, one side of each trough adapted to shield secondary electrons bombarded from the surface of the other side by electrons entering through the openings in the disc from which said vanes are stamped.

5. A dynode disc for electron multipliers having vanes formed into radial troughs positioned at one side of the disc and the bisecting plane of the troughs being parallel to and spaced from the disc, one side of the trough being integrally joined to the disc and the other side facing an opening in the disc formed by the cut-out vane of an adjacent trough.

6. A dynode disc for electron multipliers having vanes formed into radial troughs positioned at one side of the disc and the bisecting plane of the troughs being parallel to and spaced from the disc, one side of the trough and a part of its outer end being integrally joined to the disc and the other side of the trough facing an opening in the disc formed by the cut-out vane of an adjacent trough.

7. A multiplier for television pick-up tubes comprising a plurality of axially aligned and spaced discs constructed as outlined in claim 1, with alternate discs positioned with the troughs facing in opposite directions with one side of a trough overlapping a side of a trough of an adjacent disc, and a cathode beam gun extending through the central holes of the discs and insulated therefrom.

8. A circular dynode disc for electron multipliers having a plurality of radial openings, a plurality of radial troughs joined to the disc at the edges of said openings to face in the same peripheral direction, the bisecting plane of the troughs being parallel to the plane of the disc.

9. A dynode disc for electron multipliers having a plurality of openings, vanes joined to said disc at the sides of said openings and extending at an angle to one side of the disc and additional vanes joined to said disc at said sides of the openings and extending at an angle to the other side of the disc to form troughs with the first mentioned vanes.
